UNITED STATES PATENT OFFICE.

FRANK B. CHURCHILL, OF HASTINGS, MICHIGAN.

WASHING-MACHINE.

SPECIFICATION forming part of Letters Patent No. 673,194, dated April 30, 1901.

Application filed September 12, 1900. Serial No. 29,819. (No model.)

To all whom it may concern:

Be it known that I, FRANK B. CHURCHILL, a citizen of the United States, residing at Hastings, in the county of Barry and State of Michigan, have invented a new and useful 5 Washing-Machine, of which the following is a specification.

The present invention relates to improvements in oscillating washing-machines, the 10 object being to provide a novel construction and arrangement of the interior portion of the body whereby the clothing or other articles placed within the same are more thoroughly agitated and the air and water forced through 15 the articles, thus quickly and thoroughly removing the dirt therefrom without injuring the fabric by unnecessary rubbing or friction.

In order that the invention may be readily understood, the preferred form of construction 20 is illustrated in the accompanying drawings and described in the following specification, of which said drawings form a part, and in which—

Figure 1 is a perspective view of the machine complete and showing a portion of the wall of the body broken away to illustrate 25 more clearly the interior construction of said body. Fig. 2 is a vertical longitudinal sectional view of the same. Fig. 3 is a vertical 30 cross-section on the line 3-3 of Fig. 2.

Similar numerals of reference designate corresponding parts in the several figures of the drawings.

In carrying out the invention a washer- 35 body 10 is provided, to the bottom of which is preferably secured rockers 11, which are adapted to operate upon a base-frame 12 and are held in place by retaining-spurs 13, which project from the lower edge of said rockers 40 and fit in notches 14 in the base-frame 12. An operating-handle 15 is secured to one side of the body 10, whereby it may be rocked upon said base 12. The washer-body 10 is preferably formed with curved end lobes or compartments 16 and a central upwardly-projecting neck 17, forming the entrance-opening, which is arranged to be closed by a flat cover 18, having a central steam-escape aperture 19.

Located within each end lobe 16 is a flat 50 imperforate division plate or board 20. Each division-board inclines downwardly from the end wall of the lobe, within which it is lo-

cated, extending transversely across the machine-body from side to side thereof, and acts as an air-tight partition between the two air-chambers 21 and 22, formed, respectively, above and below the same.

Secured to the opposite inner end walls of the neck 17 are supporting-cleats 23, upon the upper edge of which the cover 18 rests 60 when in place. The lower edges of these cleats project below the lower edge of the neck well into the washer-body, being preferably beveled upon their rear faces, and form retarding-flanges 24, which also extend 65 transversely across the body in parallelism to the said division-boards.

In the operation of the machine as the body is tilted in one direction the contents gravitate to one end, and the water, rushing into 70 the chambers 21 and 22, compresses the air contained within the same, while the greater bulk of the clothing is stopped by the edge of the division plate or board 20. The confined air immediately reacts against the wa- 75 ter and forces the same through the clothing with sufficient force to remove the dirt therefrom. Upon tilting the body in the opposite direction the contents pass toward the opposite end of the machine and the above operation is repeated. The bulk of the clothing, however, in passing from one end to the other strikes against the depending flanges 24, which retards the same and turns it about, so as to present other portions to the action of 80 the air and water. These flanges also direct the water downward, and thus prevent its splashing out through the cover or aperture, besides retarding the movement of the clothing to such an extent as to cause the more 85 rapidly moving water to surge therethrough.

By this construction it will be seen that a washing-machine body is provided in which the water is forced rapidly and thoroughly through the clothes placed therein, said 90 clothes being turned to present fresh surfaces for the water to act upon on each movement of the body.

From the foregoing it is thought that the construction, operation, and many advantages of the herein-described invention will be apparent to those skilled in the art without further description, and it will be understood that various changes in the size, shape,

proportion, and minor details of construction may be resorted to without departing from the spirit or sacrificing any of the advantages of the invention.

Having thus described my invention, what I claim as new, and desire to secure by Letters Patent, is—

In an oscillating washing-machine, the combination with a tilttable body having curved end lobes and an upstanding neck, of imperforate division-boards located within the end lobes about midway of the same and projecting downwardly from the end walls thereof forming separate air-chambers above and below the same, and cleats secured to the oppo-

site inner end walls of the neck and depending into the body to form retarding-flanges, the upper edges of said cleats forming supporting means for a cover arranged to close the neck-opening, and the lower edges of the 20 cleats being in substantial parallelism with the division-boards.

In testimony that I claim the foregoing as my own I have hereto affixed my signature in the presence of two witnesses.

FRANK B. CHURCHILL.
